UNITED STATES PATENT OFFICE.

HERBERT J. TARR, JR., OF CHICAGO, ILLINOIS.

DENTAL PLATE.

SPECIFICATION forming part of Letters Patent No. 782,627, dated February 14, 1905.

Application filed April 27, 1904. Serial No. 205,065.

To all whom it may concern:

Be it known that I, HERBERT J. TARR, Jr., a citizen of the United States, residing at Chicago, in the State of Illinois, have invented 5 certain new and useful Improvements in Dental Plates, of which the following is a specification.

My invention relates to fixtures for holding false teeth in the mouth, and particularly to 10 the construction of a suction chamber for holding the dental plate in place. The objects of the invention are, to provide a dental plate with a superior suction device which is comfortable to the wearer; to provide improved 15 means for fastening the suction diaphragm in place in the dental plate; to provide a removable suction diaphragm, and to generally improve the structure and operation of dental plates. These objects, and other advantages 20 hereinafter to appear, I attain by means of the construction illustrated in preferred form in the accompanying drawings, wherein—

Figure 1 is an under plan view of a dental plate or false palate, having my improvements 25 applied, and

Figure 2 is a vertical cross section along line (2) in Figure 1, and Figure 3 is a modification.

In the ordinary construction of dental plates 30 the suction cavity is formed by the insertion of a small metallic plate in the middle of the palate, and this is usually fixed in place by being fused into the substance of the dental plate, and is not renewable. It is extremely 35 difficult to make a metallic suction plate of such form as to be comfortable to the mouth and to fit hermetically in its place in the dental plate, and when it becomes perforated or distorted, the entire dental plate is rendered useless until 40 softened and remolded in order to insert another suction plate. In order to overcome these difficulties and others, I provide the dental plate 3 with a removable suction chamber formed by the use of a diaphragm 5. In 45 order to maintain the diaphragm in place, I provide an opening in the dental plate and surround it by a U-shaped metallic ring 6 which is anchored by projections 7 in the hard rubber of the plate in the molding of the latter, and this presents a circumferential grooved

ring around the periphery of the cardioid form of opening in the plate. As seen more clearly in Figure 2, I secure the diaphragm 5 in place by inserting its edges in the opening of the ring 6 and then expand and fix therein a metallic 55 wire ring 8 to hold it firmly in place. The diaphragm 5 is preferably made of soft rubber arched downward, and both edges of ring 6 have rounded beads to avoid cutting it. The recess under diaphragm 5 is thus capable of 60 contraction and expansion and may vary with the suction, and the diaphragm will readily resume its first position and accommodate itself to the mouth and will feel comfortable therein. When the suction diaphragm becomes injured 65 or distorted in any way, or for any reason it is desired to be renewed, this may readily be done by removing the ring 8, and taking it out of the grooved ring 6, and a new diaphragm may be placed therein. Other advantages 70 of the device will readily occur to those familiar with the art.

While I have described the use of soft rubber for the diaphragm, it is obvious that any yielding substance could be used in place 75 thereof without departure from the spirit of my invention, and further that, if desired, any suitable auxiliary means, such as the strip of spring steel 9 mounted above the diaphragm, might be employed to aid it to resume 80 its original position, shown in Figure 3.

Having thus described my invention and illustrated its use, what I claim as new, and desire to secure by Letters Patent, is the following:

1. A dental plate having an open space therein and a removable diaphragm temporarily secured in the space and forming a suction chamber, substantially as described.
2. A dental plate composed of hard material 90 and provided with a removable suction chamber formed by a yielding diaphragm hermetically sealed in an opening in said dental plate.
3. The combination with a hard rubber dental plate having an opening therein, a grooved 95 ring sealed in the plate in the periphery of the opening, and a soft rubber diaphragm covering said opening and means to fix it in said hollow ring, substantially as described.
4. The combination with a dental plate hav- 100

ing a circumferential channeled ring around the opening therein and anchored in the material of the plate, a suction diaphragm having its edges doubled and placed in the channel of the annular ring, and a holder ring sprung into place in the said annular ring to anchor the edges of the diaphragm, substantially as described.

In testimony whereof I have hereunder signed my name in the presence of the two sub-¹⁰ scribed witnesses.

HERBERT J. TARR, JR.
